GATE

Filed Aug. 11, 1924

3 Sheets-Sheet 3

A technical line drawing of a wooden structure, possibly a gate or fence panel. The drawing shows a vertical post on the right (18) with a horizontal rail (19) and a curved top rail (20). A diagonal brace (16) runs from the middle of the post to the left. A horizontal cross-brace (15) is attached to the post and the diagonal brace. A vertical post (1) is on the far left. Various other components are labeled with numbers: 2, 3, 5, 7, 10, 12, 13, 14, 16, 17, 18, 19, 21, 23, 26, and 29. The drawing is done in black ink on a white background.

UNITED STATES PATENT OFFICE.

JOHN LUNDGREN, OF SILVER CREEK, NEBRASKA.

GATE.

Application filed August 11, 1924. Serial No. 731,397.

To all whom it may concern:

Be it known that I, JOHN LUNDGREN, a citizen of the United States, residing at Silver Creek, in the county of Merrick and 5 State of Nebraska, have invented certain new and useful Improvements in Gates, of which the following is a specification.

This invention relates to gate structures, and it consists in the novel features herein-10 after described and claimed.

An object of the invention is to provide a gate structure having the panel thereof mounted for horizontal swinging and vertical sliding movement upon a hinge post, 15 there being means provided at the opposite sides of the panel and the hinge post, adapted to be manipulated by one seated in a vehicle, whereby the panel may be swung from a closed to an open position, and from an open 20 to a closed position, without necessitating the occupants of the vehicle alighting therefrom.

In the accompanying drawing:

Figure 1 is a top plan view of the gate 25 structure.

Figure 2 is a side elevational view of the same.

Figure 3 is a side elevation of the gate panel, showing the same at a closed position. 30 Figure 4 is a fragmentary sectional view of the hinge post of the gate structure and parts mounted thereon.

Figure 5 is a side elevation of the latch member used in the gate structure.

Figure 6 is a fragmentary edge elevation 35 of the gate panel showing a latching device thereon.

Figure 7 is a transverse sectional view of the hinge bolt and showing a locking means 40 for the gate operating sleeve.

The gate structure comprises a hinge post 1, which is anchored in the ground in an appropriate manner, and which is disposed opposite a latch post 2. A keeper plate 3 is 45 mounted upon the inner side of the latch post 2 and is provided at its upper edge with a recess 4, having at its ends inclined fingers 5, with outer bevelled edges 6. The keeper plate 3 is provided at a point between its ends with a vertically disposed slot 7, and

bolts 8 pass through the said slot and enter the post 2, and serve as means for holding the latch plate in position upon the post. A pin 9 is disposed transversely through 50 the hinge post 1 and its end portions project beyond the opposite sides of the said post.

A sleeve 10 is mounted for rotary and sliding movement upon the upper end of the post 1 and is provided at its lower edge with notches, adapted to engage the pin 9. Four 60 notches are provided; and they are located at equal distances apart, and the said notches have converging side edges. A bolt 11 is disposed transversely through the sleeve 10, and a rope 12 is connected at one end 65 with the said bolt 11. Loops 13 are slidably and turnably mounted upon the post 1 below the pin 9; and a gate panel 14 is secured to the said loops. A latch member 15 is pivotally mounted on the free end portion 70 of the gate panel 14, and may ride upon the bevelled edges 6 of the fingers 5 and enter the recess 4 of the keeper plate 3, whereby the said gate panel may be held closed. Bracket members 16 are secured at the opposite sides of the panel 14, and are disposed substantially diagonally with relation to the 75 said panel. Chain sections 17 are connected at their lower ends with the upper ends of the bracket members 16, and the said chain sections 17 are connected at their upper ends with the bolt 11 hereinbefore described. The chain sections 17 are disposed at opposite sides of the sleeve section 10. Angularly disposed arms 18 are mounted at 80 the upper end of the sleeve 10, and the said arms are disposed at an acute angle with relation to each other. Cables 19 are connected at one end with the arms 18 and the intermediate portions of the said cables are 85 trained over pulleys 20 journaled at the upper ends of latch posts 21, which are set in the ground at the opposite sides of the hinge post 1. The latch posts 21 carry keeper plates 3, similar to the plate which 90 is applied to the aforesaid latch post 2. The outer ends of the cables 19 are connected by means of the springs 24 with levers 23, which are fulcrumed upon lever posts 25 anchored in the ground. Springs 26 are 100 connected at one end with the intermediate portions of the levers 23, and at their other ends are connected with the lever posts 25. The springs 26 are under tension with a tendency to normally hold the free ends of the 105 levers 23 in elevated position.

The sleeve 10 and the upper portion of the hinge post 1 are provided with openings 27 and 28 respectively, which are adapted to register with each other and the pin 29 110 may be passed through the said registering openings, whereby the sleeve is held

against turning movement with relation to the post.

The operation of the gate is as follows:

When the gate panel is in a closed position as shown, in Figure 3 of the drawing, and the occupant of a vehicle approaches the gate panel and desires to open the same without alighting from the vehicle, the occupant grasps the upper end of the lever 23, and swings the said end of the lever in a downward direction whereby the cable 19, which is connected with the lever is moved longitudinally. Thus the arms 18 are swung and carry the sleeve 10 around with them. As the sleeve 10 turns, one of the chain sections 17 is wound upon the said sleeve and the gate panel 14 is lifted so that the latch 15 disengages from the recess in the keeper plate upon the latch post. Upon further swinging movement applied to the lever 23, the chain section 17 acted on exerts a pull upon the corresponding bracket 16 and the gate panel 14 is swung from a closed to an open position after which the driver of the vehicle may pass through the gate opening. When he arrives at the other side, a downward swing is exerted upon the other lever 23, whereby the movement of the parts hereinbefore described, is reversed, and the panel is swung from an open to a closed position. Should it be desired to prevent operation of the gate from a distance the pin 29 is passed through the registering perforations 27 and 28 in the sleeve and hinge post respectively.

Having described the invention, what is claimed is:

1. A gate structure comprising a hinge post and a latch post provided with a keeper plate, a sleeve rotatably and slidably mounted upon the hinge post, loops slidably and rotatably mounted upon said post, a gate connected with the loops, a latch member carried by the gate and engaging the keeper plate, said latch member being adapted to be disengaged from said plate when said gate is lifted vertically, and chain sections connected at one end with the gate

and at their opposite ends with the sleeve, said chain sections being disposed one at 50 each side of the sleeve to wrap thereon when the sleeve is rotated whereby to lift and swing said gate.

2. A gate structure comprising a post upon which a gate is adapted to be mounted, a latch post, a keeper plate mounted upon said last named post, a sleeve rotatably and slidably mounted upon the gate post, said sleeve being provided at its lower end with notches, a pin extending through and beyond the gate post and adapted to enter said notches, loops slidably mounted upon the gate post, a gate connected with the loops, chain sections connected at one end to the gate and at their opposite ends with said sleeve, there being a chain section located at each side of the sleeve and gate, operating arms for rotating said sleeve fixed thereto and extending therefrom in divergent relation, said sleeve and gate post being provided with aligned openings, and a retaining pin adapted to be inserted through said openings for preventing relative movement of the sleeve and post.

3. A gate structure comprising a hinge 75 post, a latch post, a keeper plate thereon, a sleeve turnably mounted upon the hinge post, loops slidably mounted upon the hinge post, a gate panel carried by the loops and having a latch adapted to engage the keeper plate, chain sections connected at one end with the panel and connected at their other ends with the sleeve, there being a chain section located at each side of the sleeve, angularly disposed arms fixed to the upper 85 end portion of the sleeve, latch posts disposed at opposite sides of the hinge post and having keeper plates, lever posts disposed beyond the latch posts, cables connected at their inner ends with the arms and trained over the latch posts, and spring supported levers fulcrumed upon the lever posts and connected with the outer ends of the last mentioned cables.

In testimony whereof I affix my signature.
JOHN LUNDGREN.
